DESIGN FOR A VANITY BOX

Le Roy P. Root, Brooklyn, N. Y., assignor to Scovill Manufacturing Company, Waterbury, Conn., a corporation of Connecticut

Application August 2, 1944, Serial No. 114,681

Term of patent 3½ years

(Cl. D86—10)

To all whom it may concern:

Be it known that I, Le Roy P. Root, a citizen of the United States, residing at Brooklyn, county of Kings, State of New York, have invented a new, original, and ornamental Design for a Vanity Box, of which the following is a specification, reference being had to the accompanying drawing, forming part thereof.

Fig. 1 is a top plan view of a vanity box embodying my new design in closed position;

Fig. 2 is a side elevation thereof;

Fig. 3 is a front elevation thereof;

Fig. 4 is a transverse sectional view taken along the line 4—4 of Fig. 3, and

Fig. 5 is a perspective view of the same in open position.

I claim:

The ornamental design for a vanity box, substantially as shown.

LE ROY P. ROOT.
